GARDEN BENCH

Filed May 10, 1929

Inventor
William Hankinson

By Clarence O'Brien
Attorney

UNITED STATES PATENT OFFICE

WILLIAM HANKINSON, OF AIKEN, SOUTH CAROLINA

GARDEN BENCH

Application filed May 10, 1929. Serial No. 362,067.

The present invention relates to a garden bench and the like and has for its prime object to provide a wheeled structure including three legs with the wheel so disposed that by tilting the bench all the weight may be placed on the wheel so that the bench is readily movable from place to place.

Another very important object of the invention resides in the provision of a garden bench or the like constructed with legs and a single wheel which functions as a leg when the bench is normally disposed for seating purposes and is so arranged beyond one end of the bench and to one side so that the bench may be tilted a slight bit for moving the bench on the wheel without causing any of the legs to scrape along the ground.

A still further very important object of the invention resides in the provision of a bench of this nature which is exceedingly simple in its construction, inexpensive to manufacture, strong and durable, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a front elevation of the bench embodying the features of my invention, and Figure 2 is a top plan view thereof.

Referring to the drawings in detail it will be seen that numerals 5 denote a pair of spaced parallel coextensive bars which are formed at one end into handles 6 and at the other ends are formed with depending bearing blocks or plates 7 in which are journaled the ends of an axle shaft 8 with a wheel 9 fixed thereto off center toward the front.

A leg bar 10 is fixed to the front bar 5 intermediate its ends so as to depend downwardly from the bar 5 and also rise upwardly therefrom. This leg bar 10 is located adjacent the handle 6 of said front bar 5. Bars 11 rise from the bar 5 adjacent the bearing blocks 7 fixed thereto.

A leg 10' is fixed to the rear bar 5 adjacent the handle thereof and is constructed the same as the leg bar 10. Arm rests 12 are mounted on the upper ends of the leg bars 10, 10' and bars 11 and a back 14 is fixed across the rear end of these arms.

A seat 15 is mounted between the bars 5 in any suitable manner. The important feature of this mobile bench is the location of the wheel 9 which is disposed at one end of the bench structure and offset toward the front thereof at the corner without a leg so that it is only necessary to lift up on the handle 6 and slightly tilt the bench forwardly so that it may be readily moved from place to place without the nuisance of any legs scraping along the ground or engaging any upwardly protruding obstacles on the ground, and furthermore a saving of material is the result of using the wheel 9 as one of the legs.

It is thought that the construction, utility and advantages of this invention will now be quite apparent to those skilled in this art without a more detailed description thereof.

The present embodiment of the invention has been described in detail merely for the purposes of exemplification since in actual practice it attains the features of advantage enumerated as desirable in the statement of the invention and the above description.

It will be apparent that changes in the details of construction, in the combination and arrangements of parts may be resorted to without departing from the spirit or scope of the invention as hereinafter claimed or sacrificing any of its advantages.

Having thus described my invention, what I claim as new is:

In a bench structure of the class described, a pair of spaced parallel coextensive bars formed at one end with handles and having at their other ends depending bearing blocks, an axle journaled in said blocks, a wheel on said axle offset toward the front of the bench, legs on said bars adjacent the handles thereof, a seat between said bars, posts secured to the bars adjacent the opposite ends thereof and extending upwardly therefrom, the rear-most of said bars having depending integral

extensions constituting supporting legs, transverse arm rests secured on the upper ends of the posts and a longitudinally extending back rest mounted on the arm rests at one end thereof.

⁵ In testimony whereof I affix my signature.

WILLIAM HANKINSON.
